UNITED STATES PATENT OFFICE

154,765

DESIGN FOR A TROPICAL TABLE LAMP

Earmon A. Garner, Key West, Fla.

Application October 22, 1947, Serial No. 142,094

Term of patent 7 years

(Cl. D48—20)

To all whom it may concern:

Be it known that I, Earmon A. Garner, a citizen of the United States of America, residing at Key West, in the county of Monroe and State of Florida, have invented a new, original, and ornamental Design for a Tropical Table Lamp, of which the following is a specification, reference being had to the accompanying drawing, forming a part thereof wherein:

Figure 1 is a perspective view of a tropical table lamp, showing my new design

Figure 2 is a view similar to Figure 1 illustrating a rear face of the lamp

Figure 3 is a view looking into one edge of the lamp, and

Figure 4 is a view similar to Figure 3 looking into the opposite end of the lamp.

The dominant features of my design reside in the portions shown in full lines.

I claim:

The ornamental design for a tropical table lamp, as shown, and described.

EARMON A. GARNER.
